(57) **CLAIM**

We claim the ornamental design for a parking meter mechanism, as shown and described.

DESCRIPTION

FIG. 1 is a first front perspective view from above of a parking meter mechanism of the claimed design;

FIG. 2 is a front view of the claimed design of FIG. 1;

FIG. 3 is a rear view of the claimed design of FIG. 1;

FIG. 4 is a right side view of the claimed design of FIG. 1;

FIG. 5 is a left side view of the claimed design of FIG. 1;

FIG. 6 is a top view of the claimed design of FIG. 1;

FIG. 7 is a bottom view of the claimed design of FIG. 1;

FIG. 8 is a second front perspective view from above of the claimed design of FIG. 1;

FIG. 9 is a first front perspective view from below of the claimed design of FIG. 1;

FIG. 10 is a second front perspective view from below of the claimed design of FIG. 1;

FIG. 11 is a first rear perspective view from above of the claimed design of FIG. 1;

FIG. 12 is a second rear perspective view from above of the claimed design of FIG. 1;

FIG. 13 is a first rear perspective view from below of the claimed design of FIG. 1; and,

FIG. 14 is a second rear perspective view from below of the claimed design of FIG. 1.

The structural features depicted by broken lines in the drawing have been shown for the purpose of illustrating portions of the parking meter mechanism that form no part of the claimed design.
